UNITED STATES PATENT OFFICE

136,653

DESIGN FOR A COMBINED FUMES REMOVAL HOOD AND LIGHTING FIXTURE

Morris Cohen, Kansas City, Mo., and Gerald A. Jorgenson, Chicago, Ill., assignors to Interstate Bakeries Corporation, Kansas City, Mo., a corporation of Delaware

Application September 1, 1943, Serial No. 111,032

Term of patent 14 years

To all whom it may concern:

Be it known that we, Morris Cohen, a citizen of the United States, residing at Kansas City, county of Jackson and State of Missouri; and Gerald A. Jorgenson, a citizen of the United States, residing at Chicago, county of Cook and State of Illinois, have invented a new, original, and ornamental Design for a Combined Fumes Removal Hood and Lighting Fixture, of which the following is a specification, reference being had to the accompanying drawing, forming a part thereof.

Figure 1 is a perspective view of a combined fumes removal hood and lighting fixture showing our new design.

Figure 2 is an end elevational view of Figure 1.
We claim:

The ornamental design for a combined fumes removal hood and lighting fixture, substantially as shown.

MORRIS COHEN.
GERALD A. JORGENSEN.
